FLOATING ROOF FOR OIL STORAGE RESERVOIR

George A. McCommon, Caracas, Venezuela, assignor to Jersey Production Research Company, a corporation of Delaware

Filed Dec. 29, 1958, Ser. No. 783,516

5 Claims. (Cl. 220—26)

This invention relates to covering means for reservoirs for the storage of liquid materials. It relates particularly to such covering means which float directly upon the surface of the liquid material stored in the reservoir. It relates more particularly to such floating covering means which can move freely up and down through the whole depth of the reservoir as liquid material is pumped thereto or withdrawn therefrom, and it relates more particularly still to such floating covering means capable of full depth up and down motion in a reservoir wherein the stored liquid material is a petroleum hydrocarbon such as crude oil.

When petroleum hydrocarbon liquids such as crude oil are to be stored in large quantities, it may be economically desirable to effect such storage in reservoir excavations or earth-embanked enclosures rather than in steel tanks. It will be advisable that an oil storage reservoir, if used, be provided with a covering or roof. The principal purposes of such a roof are to prevent contamination of the stored liquid and reduce evaporation losses. Roofs for oil storage reservoirs, which will often be characterized by sloping or irregularly shaped sides, are of two kinds presently known to the art, fixed and fixed-floating.

The fixed roof, while serving well enough to protect stored oil from contamination, has associated with it the problems of substantial vapor loss rates during emptying and filling of the reservoir, and the existence of a dangerous combustible mixture in the vapor space between the surface of the oil and the roof. The fixed-floating roof which is a structure that floats on the oil surface but is susceptible of vertical displacement within a narrow range only, solves the aforesaid problems of vapor or evaporation loss and presence of a combustible mixture, but adds the expense of pumping water into or draining it from the bottom of the reservoir whenever oil is being taken from or supplied to the reservoir in order that the upper oil surface may be maintained at a substantially constant level. Further more, the use of a water bottom introduces a possible means of contamination, and increases the difficulty of gaging by requiring accurate determination of the oil-water interface level.

According to the present invention, a roof for oil storage reservoirs is provided which substantially reduces evaporation loss rates and the dangers due to the presence of a combustible mixture in comparison with the fixed roof, and likewise substantially reduces dual pumping requirements and the possibility of water-in-oil contamination in comparison with the fixed-floating roof by floating directly on the stored oil and being capable of full up and down movement through conformation to the shape of the reservoir sides as the reservoir is filled and emptied.

In one apparatus embodiment of this invention, the floating roof for an oil storage reservoir comprises a plurality of initially discrete, rectangular pontoons bolted together to form a roof center section, and an array of special rectangular pontoons which overlap and are slide-

2

ble with respect to each other to make up the roof side or edge sections. The roof may be made substantially gas tight by using strips of neoprene or other appropriate material between the center section pontoons and curtains or bellows sections of such material to overlay or underlie the sliding connections on the side selection pontoons.

The nature and substance of this invention may be more clearly perceived and fully understood by referring to the following description and claims taken in connection with the accompanying drawings in which:

Fig. 1 represents a plan view of an oil storage reservoir provided with a floating roof according to this invention, the liquid level in the reservoir being substantially at its full height.

Fig. 2 represents a view in sectional elevation through an oil storage reservoir provided with a floating roof according to this invention taken along line 2—2 of Fig. 1.

Fig. 3 represents a plan view of a typical pontoon used in the assembly of the floating roof center section including certain fittings used on pontoons at the edges and corners of the assembly, but not including the rain water drainage fitting.

Fig. 4 represents a view in sectional elevation through a typical pontoon used in the assembly of the floating roof center section taken along line 4—4 of Fig. 3.

Fig. 5 represents an elevation view, partly in section, through a typical rain water drainage fitting and hose provided on the individual pontoons of the floating roof center section assembly.

Fig. 6 represents a side elevation view of a typical cable connection fitting used on certain edge pontoons of the floating roof center section and on all of the pontoons of the floating roof side sections.

Fig. 7 represents an end view in sectional elevation of a typical cable connection fitting taken along line 7—7 of Fig. 6.

Fig. 8 represents a plan view of the typical cable connection fitting shown in side elevation in Fig. 6.

Fig. 9 represents a plan view of a typical corner connection of four pontoons of the floating roof center section.

Fig. 10 represents a view in sectional elevation through a floating roof side section taken along line 10—10 of Fig. 1, the liquid level in the reservoir being substantially at its full height.

Fig. 11 represents a view in sectional elevation showing a typical end connection of two abutting pontoons of a floating roof side section taken along line 11—11 of Figs. 1 and 10.

Fig. 12 represents a view in sectional elevation through a floating roof side section on the same plane as Fig. 10, but in this case with the reservoir substantially drained of liquid.

Referring now to the drawings, particularly Figs. 1 and 2, 20 designates an earth embankment of closed configuration which comprises the bounding wall of a reservoir space 22 wherein hydrocarbon liquids such as crude oil may be stored. This reservoir space is characterized by a substantially horizontal and rectangular bottom having flat wall surfaces sloping upwardly and outwardly from the edges thereof. It should be noted, however, that the internal corners of embankment 20 are reentrant. The side wall surfaces in these corner regions should be considered as cut straight up and down rather than sloping.

Running along the reservoir wall surfaces interiorly near the top thereof except on the vertical corner walls are earth-embedded concrete strips 24. These serve as anchoring means for certain elements of the floating roof structure of this invention. In particular, they anchor the hairpin-formed cable securing bars 26 from

which extend the pontoon cables 28, the nature and purpose of which will be more completely disclosed presently.

The floating roof structure, shown in its position of maximum elevation corresponding to a full reservoir, includes a center section and four side sections. Considering first the center section, this is made up of a plurality of individual rectangular pontoons which can be joined by bolting or any other appropriate method in a number to give a center section of the desired overall dimensions.

The majority of the center section pontoons, those away from the edges and corners, are of a uniform class designated A. The edge pontoons of the center roof section, except for the four at the corners thereof, are designated as belonging to class B, while these corner pontoons are designated class B¹. Differences between the class A, B, and B¹ pontoons will be indicated presently. Whatever its class, however, each pontoon of the floating roof center section may be provided with one or more rainwater drainage hoses 30 descending from appropriate through fittings, and at least one center section pontoon should be so equipped. These hoses must each be of sufficient length that water flowing downwardly through them will be conveyed to the very bottom of reservoir space 22 even with the floating roof at its full height. In this way the possibility of mixing oil and water will be minimized, and what water does descend through hoses 30 may be drawn off conveniently through a bottom drain line of the reservoir. The reservoir must, of course, be provided with appropriate overflow means to prevent lifting of the roof beyond the condition shown in Figs. 1 and 2, whether by excess oil supply or long-continued rainfall.

The four sections of the floating roof structure each include one or more sets of overlapping plates and pontoons, these sets being abutted in any number needed to give the required length of side section to fit closely to the vertical walls of the reentrant corner regions of embankment 29. Each set of side section elements comprises a plate K hinged to the adjacent concrete strip 24, and special pontoons J, H, G, F, E, D, and C extending in that order toward the center section of the floating roof structure, that is, in a direction here considered inward. The K plate has a variable overlap on the J pontoon; the J pontoon has a variable overlap on the H pontoon, and so on with the C pontoon finally having a variable overlap on one or more less than one B pontoon. As shown, the K plate and the J, H, G, F, E, D, and C pontoons have lengths equal to about two adjacent B pontoons. This relation is not critical.

The extent to which any adjacent members of a set of side section elements are overlapped will vary with the level of liquid in the reservoir, in general the higher the level the greater the overlap. At any level of liquid, however, the several elements of a side section set are tied together by at least one cable 28. Any given cable 28 upon departing from its securing bar 26 will pass over the adjacent K plate to a fixed anchoring point on the J pontoon. From there it will proceed to anchoring points on the H, G, F, E, D, and C pontoons successively. A few cables 28, perhaps every sixth, may extend from the C pontoons to anchoring points on the B pontoons. With the side section elements in their condition of greatest overlap as they are in Figs. 1 and 2, all cables 28 will be slack between their several anchoring points. The movement of the side section elements whereby these cables are brought from a slack to a taut condition will be described presently.

Referring next to Figs. 3 and 4, 32 designates a center section pontoon deck member of rectangular form, to the underside of which are welded or otherwise oil and water tightly fitted four mitered trough-like flotation members 34 whereby a buoyancy chamber is created. The flotation members may slightly overlap and have edges above the deck member. This construction is the same for

all A, B, and B¹ class pontoons with the exception that for the class B¹ pontoons one corner of each is made reentrant along lines OX and OY, appropriate end closure plates being applied to flotation members 34 whose mitered joint is so interrupted. This corner will be the one adjacent a reentrant corner of earth embankment 20.

Deck member 32 is characterized by at least one through hole, conveniently located centrally, for the drainage of rain water. It may also be characterized by certain fittings. These may include an angle stop piece 36 parallel with one deck edge, another angle stop piece 38 parallel with an adjacent edge, a cable connector assembly 40 abutting at least one of the angle stop pieces 36 as shown, and an angle connector clip 42 at each corner except reentrant ones. Clips 42 may, however, be mounted instead on the edges of flotation members 34 where these overlap deck member 32.

Class A pontoons will have none of these fittings except the connector clips 42. Class B pontoons will each have one angle stop piece, for example 38, and four corner connector clips 42. A few class B pontoons will have a cable connector assembly 40 abutting this angle piece. Class B¹ pontoons will each have both angle stop pieces 36 and 38, and may have cable connectors 40 abutting thereagainst. They will also each have three connector clips 42 on their normal corners. On pontoons of class B¹ the stopping or outward faces of angle stop pieces 36 and 38 should be aligned with the reentrant corner edges OX and OY.

Referring next to Fig. 5, the deck member 32 of an individual center roof section pontoon is provided with a short, internally threaded sleeve 42 welded to its underside coaxially with the rainwater drainage hole. A pipe nipple 44 extending from the upper end of drainage hose 30 is held in sleeve 42 by an externally and internally threaded cap or plug 46 which is provided with appropriate wrench slots in its upper surface. Secure attachment of hose 30 to pipe nipple 44 is effected by a compression strap or band 48. A convenient feature of the structure shown in Fig. 5 is that it allows drainage hoses 30 to be installed from the upper side of the floating roof center section after this section has been fully assembled otherwise, and is in place and floating in an oil storage reservoir. Assuming cap 46 to be tight on nipple 44, only a screwing or unscrewing of the cap in sleeve 42 is needed for hose replacement or removal.

Referring next to Figs. 6, 7, and 8, the cable connector assembly 40 comprises a foundation angle piece 50 which is welded to a pontoon deck member, a fixed 50 clamping plate 52 welded to foundation piece 50, and a removable clamping plate 54 which may be secured to the fixed clamping plate by appropriate means such as nuts and bolts. Plates 52 and 54 are grooved to accommodate a pontoon cable 28 which, being looped where it passes through its securing bar 26 at the reservoir wall, will appear at the connector as two parallel strands. The structure illustrated in Figs. 6, 7, and 8 may be used not only on class B and B¹ pontoons of the floating roof central section as indicated already, but also on class J, H, G, F, E, D, and C pontoons of the floating roof side sections to provide the aforementioned cable anchoring points on these pontoons.

Referring next to Fig. 9, pontoons of the A, B, and B¹ classes are brought together at square, four-corner connections which are effected by means such as nuts 56 on bolts 58 passing through holes in adjacent angle connector clips 42. The bolts should have a somewhat loose fit through the clips for ease of assembly of the floating roof center section. Strips of sealing material 60 such as neoprene may be interposed between abutting pontoons, and there located by any suitable means to make the floating roof center section substantially gas tight. For example, these strips might be cemented to one or the other of a pair of abutting pontoon surfaces,

or they might be loose pieces configured in a T-shape to engage abutting pontoon edges. Likewise, expansion joints of any suitable kind may be installed between pontoons of the floating roof center section at such intervals as may be required by good design practice for the range of operating temperatures anticipated.

Referring next to Fig. 10, the structure of a side section of the floating roof of this invention, particularly the overlapping relationship of the several major elements thereof, may be seen in considerable detail. Plate element K comprises a plate member 62 fitted with wooden bearing members 64 and 66 running along its edges on the underside parallel with the wall of the reservoir. Bearing member 64 is rather loosely engaged with bracket 68 on concrete strip 24, and maintained in such engagement by bracket 70 thereabove. This arrangement provides a hinged connection of the K plate on the reservoir wall. Bearing member 66 rests slidably upon the deck plate of the J pontoon adjacent the hinged K plate. The structures of the J, H, G, F, E, D, and C pontoons are mutually similar in form and fittings although they differ in some dimensions. The G pontoon will be particularly described, and this description will be generally applicable to the other side section floating elements.

The G pontoon comprises a deck plate 72 and a flotation member 74. The latter is of partially arcuate form and is fastened oil and water-tight to the underside of the deck plate toward its outer edge and parallel thereto to form a buoyancy chamber. The outer edge of the flotation member may overlap and extend slightly above the outer edge of the deck plate. A wooden bearing member 76 is secured to plate 72 on its underside along the inner edge. This bearing member rests slidably upon the deck plate of the adjacent F pontoon. On the upper surface of deck plate 72 there is an angle stop piece 78 extending parallel with the reservoir wall, and having its stopping surface directed outwardly. As it furnishes a banking means for the wooden bearing member of the H pontoon, this stop piece provides one limit to the overlap of and relative motion between the H and G pontoons. A cable connector assembly 40 is also provided on the upper surface of deck plate 72 adjacent to and inwardly of angle stop piece 78.

Since Fig. 10, like Figs. 1 and 2, represents the condition of a full reservoir with the floating roof at its highest level, the several elements of the side section of the roof appearing in Fig. 10 are shown with their greatest degree of both mutual overlap and final inward overlap on the adjacent class B pontoon of the center section of the roof. Note should be taken that in this circumstance all runs of cable 28 between securing bar 26 and the several connectors 40 will be slack. Note may be taken also at this point of a structural feature of the reservoir itself, namely the pipe member 80 embedded in or otherwise retained on the sloping wall with at least some of its surface projecting above the wall. The purpose of this pipe is to provide a bearing surface for the flotation members of the side section pontoons when the reservoir is drained with attendant lowering of the roof.

To help render the floating roof side sections substantially gas tight, sliding or flexible seals may be provided between overlapping members thereof. A simple sealing means of this kind would be a neoprene sheet or blanket laid over the deck plates of the E and D pontoons for example. A possible objection to such a seal would be that it might be difficult to fit a properly operable blanket around the various fittings on the deck plate upper surfaces, not only those fittings shown in Fig. 10 but also the several deck plate stiffeners which would almost certainly be present in practice. Accordingly it may be desirable to effect sealing on the under side of the roof as by a neoprene bellows sheet 82 secured along one edge to the bottom of the deck plate of the E pontoon, and

along the other to the upper outward surface of the flotation member of the D pontoon, and having considerable slack with the E and D pontoons in their condition of greatest overlap.

Referring now to Fig. 11, two H pontoons are shown sectionally in end-to-end abutment looking inwardly toward the center of the reservoir on a plane through the buoyancy chambers of these pontoons. Each pontoon comprises a deck plate member 84, a flotation member 86 secured thereto, and a flotation member closure piece 88 which determines the end boundary of its buoyancy chamber. Each pontoon may also have an angle clip or bracket 90 along the end-abutting edge of its deck plate 84 which is suitably pierced to allow use of joining means such as nut 92 on bolt 94. This general system of end-to-end connection may be used for all other side section pontoons besides the H pontoons, and also for the hinged K plates.

Although not specifically illustrated, it is evident that 20 interposed sealing means such as neoprene strip 60 appearing in Fig. 9 may be used to render the butt joints of the side section pontoons and hinged plates substantially gas tight. Likewise, expansion joints of any appropriate kind may be used between side section end-abutting members at appropriate intervals. In view of the fact that 25 the floating roof side sections must work in what are substantially fixed distances between vertical walls at the reentrant corners of the reservoir, considerations of expansion and contraction may be quite important if the 30 reservoir is located in a region subject to temperature variation through an appreciable range.

Further on the matter of sealing, there will be a vertically variable relationship, and, therefore, working clearances between the ends of the extreme K plates and 35 J, H, G, F, E, D, and C pontoons of each of the floating roof side sections on the one hand and the reservoir wall reentrant corner surfaces wherebetween the side sections are located on the other. These clearances may be sealed against gas escape by an appropriate means such as neoprene curtains or ballons on the ends of the moving plate and pontoon elements. Gas seals of a similar nature may be provided for the working clearances between the OX and OY reentrant corner surfaces of the B¹ pontoons of the floating roof center section, and the 40 reentrant corners of the reservoir wall.

Referring next to Fig. 12, the floating roof side section elements and adjacent center section elements appearing in Fig. 10 are shown in their fully lowered condition, that is, with the reservoir substantially drained 50 of liquid. The flotation members of the J, H, G, F, E, D, and C pontoons are resting on pipe 80 in the reservoir wall while the B and A pontoons are at rest on the reservoir bottom. The side section elements from the K plate through the C pontoon are in a condition of only 55 a slight degree of overlap from one to another, as are the C and B pontoons. The several runs of cable 28 between its anchoring points on the reservoir wall and the pontoons are taut, and the exemplary bellows seal 82 between the E and D pontoons has been extended 60 from its condition in Fig. 10.

The component parts of an apparatus embodiment of this invention having been described individually and in their relations one to another, the overall operation of this apparatus will now be considered. In this consideration certain additional design requirements of this apparatus embodiment will be made apparent.

Assume the floating roof to be in the condition shown in Figs. 1, 2, and 10, that is, floating at its highest level with the reservoir volume 22 substantially full of liquid 70 material such as crude oil. Imagine now that oil is drained from the reservoir. The floating roof center section comprising the A, B, and B¹ pontoons will sink straight down with no change in shape. Likewise, the side sections exclusive of the K plates will descend without deflection. The K plates will, however, pivot down,

wardly around brackets 68. Bearing members 66 of the K plates will slide relatively outwardly along the deck plates of the J pontoons as overlap between the K plates and the J pontoons decreases. Also, and very important, slack will be taken out of the runs of cables 28 between securing bars 26 at the reservoir wall rim and connector fittings 40 on the J pontoons.

With continued removal of oil from the reservoir, the J pontoons will descend to such level that their partially arcuate flotation members land on pipes 80 set in the sloping walls. The length of each run of cable 28 between a securing bar 26 and a connector fitting 40 on a J pontoon should be such that this run will go taut just as the J pontoon flotation member comes in contact with pipes 80. At this time bearing members 66 of the K plates should still be in contact with the deck plates of the J pontoons, although now rather close to the outer edges of these plates. This will represent the condition of greatest relative outward movement of bearing member 66 of the K plate on the deck plate member of the J pontoon, this deck plate still being horizontal.

As more oil is removed from the reservoir there will be loss of buoyant force on the J pontoons while the H, G, F, E, D, and C pontoons and the floating roof center section continue their descent. The J pontoons will tip downwardly to align their deck plates with the hinged K plates. Such tipping will not, however, take place by rotation about the initial points of contact of the J pontoon flotation members on wall pipe 80. Instead, the J pontoons will pivot on cables 28 which are now taut in their segments between securing bars 26 and the connector fittings 40 on the J pontoons. In the course of such pivoting action, the flotation members of the J pontoons will slide relatively upwardly along pipes 80. Likewise, bearing members 66 of the K plates will slide relatively inwardly for a short ways on the deck plates of the J pontoons.

During the tipping action of the J pontoons as they pivot on the taut segments of cables 28, the bearing members of these pontoons, corresponding to bearing members 66 and 76 of the K plates and G pontoons respectively, will be sliding relatively outwardly along the deck plates of the H pontoons. With the removal of sufficient oil from the reservoir, the flotation members of the H pontoons will land on wall pipes 80. The length of segments of cables 28 between the connector fittings on the J and H pontoons should be such that these segments go taut just as the flotation members of the H pontoons strike the wall pipes. At this time, of course, the bearing members of the J pontoons should still be in contact with the deck plates of the H pontoons, although in their furthest outward position relative thereto.

With the removal of still more oil from the reservoir, buoyant force will be lost on the H pontoons; the G, F, E, D, and C pontoons and the floating roof center section will continue their downward motion. The deck plates of the H pontoons will tilt downwardly as they pivot on the taut segments of cables 28 whereby they are connected to the J pontoons; the flotation members of the H pontoons will slide relatively upwardly along wall pipes 80, and the bearing members of the J pontoons will slide relatively inwardly for a short ways on the deck plates of the H pontoons.

It may be seen that as more and more oil is removed from the reservoir the flotation members of the G, F, E, D, and C pontoons will land in succession on wall pipes 80. As the flotation member of each pontoon does land, the cable segment whereby that pontoon is connected to the one next above and outwardly of it should go taut with various tilting and sliding actions of a nature described already taking place thereafter. During all of the foregoing, the various sliding and flexible seals provided between relatively movable members of the roof structure and the roof and the reservoir wall will be working to maintain such degree of gas tightness of the

roof as may have been provided for in the design. Finally, with the reservoir almost entirely drained of oil, the floating roof center section comprising the A, B, and B¹ pontoons will land on the reservoir bottom and the conditions shown in Fig. 12 with regard to relative positions of floating roof elements be realized.

When the reservoir is filled, the first part of the floating roof to come up will be the center section. As this section rises it will tip up the deck plates of the C pontoons, any cable segments between connectors on the B and C pontoons going slack. By the time the deck plates of the C pontoons have become horizontal these pontoons will have achieved full buoyancy. Further filling of oil into the reservoir will cause the C pontoons to rise straight up with the center section of the floating roof, and in their turn tip up the deck plates of the D pontoons.

As more and more oil is admitted to the reservoir the center section of the floating roof will continue to rise, and the E, F, G, H, and J pontoons will be brought horizontal at their deck plates and achieve buoyancy successively. Finally, with all pontoon elements going up together, the K plates will be tilted upwardly to a horizontal attitude and the conditions shown in Figs. 1, 2, 15 and 10 with regard to relative positions of floating roof elements be realized.

From the foregoing descriptions of structures and function, it may be seen that the illustrated apparatus embodiment of this invention is an articulated roof which 30 will float on a liquid surface at all levels thereof in a reservoir, and conform closely to the shape of that surface and the reservoir wall portions extending thereabove to leave a minimum amount of vapor space between itself and the liquid surface for any and all levels of filling of 35 the reservoir. The possibility of rendering this roof gas tight to any desired extent for any and all levels of filling of the reservoir has been indicated as well.

Although this invention has been described with a certain degree of particularity, it is to be understood that 40 the present disclosure has been made only by way of example, and that numerous changes in the details of construction and the combination and arrangement of parts may be resorted to without departing from the spirit and scope of this invention as hereinafter claimed.

45 What is claimed is:

1. In combination with a reservoir having a central section and at least one sloping side wall, a floating roof which comprises: a central buoyant section of approximate size of the central portion of said reservoir; at 50 least one side section having inner and outer edges including a plurality of overlapping telescoping floating members, the inner floating member being hinged to said central portion of said roof; hinge attachment means between the outer edge of said side section and the 55 reservoir wall surface; each floating member including a pontoon element, a deck on and rigidly attached to its pontoon element, said deck extending beyond said pontoon member toward the central portion of said reservoir; means to limit the overlap of the deck of one floating member with the adjacent floating member; cable anchoring means on the reservoir wall, on the top side 60 of each said deck and on said central buoyant section; a cable extending sequentially from said cable anchoring means on the reservoir wall to the cable anchoring 65 means on the floating member adjacent said reservoir wall to the cable anchoring means on the next floating member inwardly therefrom and so on to the cable anchoring means on said central section, said runs of cable being of such length as to all be slack when the roof is 70 at its greatest elevation corresponding to the condition of the reservoir having its full design content of liquid and to go taut sequentially as each of said side floating members come into contact with said reservoir wall from the reservoir being drained of liquid and the roof accordingly lowered.

2. An apparatus as defined in claim 1 in which the lower cross-sectional contour of the pontoon elements of said side floating members are at least partially arcuate.

3. An apparatus as defined in claim 1 in which below sealing sheets are provided between the underside 5 of each deck and the exterior wall of the inwardly adjacent pontoon member.

4. A roof in accordance with the combination of claim 1 in which the said central section comprises a plurality of initially discrete buoyant pontoon members 10 joined to form a single floating structure.

5. A roof as defined in claim 1 in which said side section includes at least one non-buoyant plate member having hinged attachment to said reservoir wall surfaces.
